UNITED STATES PATENT OFFICE

149,732

DESIGN FOR A COAT

David Bellsey, New York, N. Y.

Application July 29, 1947, Serial No. 140,571

Term of patent 3½ years

(Cl. D3—4)

To all whom it may concern:

Be it known that I, David Bellsey, a citizen of the United States of America, residing in New York, county of New York, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

Fig. 3 is a fragmentary front view of the coat shown in Fig. 1, with the right end of the collar drawn through the collar slit.

Fig. 4 is a fragmentary front view of the coat with the collar in open position and with the right collar lapel hanging free.

The dominant feature of my design resides in the portion shown in solid lines.

I claim:

The ornamental design for a coat, substantially as shown and described.

DAVID BELLSEY.
